ABSTRACT

A humidifier having a belt, means for moisturizing the belt, means for moving air against the belt and delivering air moisturized thereby to the ambient atmosphere, and means for selectively driving the belt *a* whenever the air moving means is operated, or *b* continuously.

1
HUMIDIFIER

BACKGROUND OF THE INVENTION

1. Field of the Invention

This invention relates to humidifiers and in particular to humidifiers having a flexible humidifying means such as a belt.

2. Description of the Prior Art

In the conventional belt type humidifier, a flexible belt is passed through a body of moisturizing liquid, such as water, and an air flow is directed through the moistened belt to deliver thusly moistened air to the ambient atmosphere. A problem arises in such belt-type humidifiers in that conventionally the belts are driven intermittently so that when the humidity conditions do not require humidification of the atmosphere, the apparatus shuts down, including the belt driving means. The exposed portions of the belt when the apparatus is shut down tend to dry out and deposits of salts dissolved in the moisturizing water are left on the belt tending to cake. Such drying and caking causes a relatively rapid degradation of the belting requiring relatively frequent servicing of the apparatus.

One solution to the problem is to provide means for driving the belt at all times thereby preventing such drying and caking. This solution has the obvious disadvantage of precluding the controlled operation of the belt affording optimum functioning of the apparatus possible where the moisturizing liquid is free or has only a low concentration of such salts. Further, discontinuation of the driving of the belt may be desired for other reasons, such as avoiding the sound of operation thereof in certain environments, etc.

SUMMARY OF THE INVENTION

The present invention comprehends an improved humidifier apparatus including means for selectively driving the belt *a* whenever the air moving means is operated, or *b* continuously.

More specifically, the invention comprehends such a humidifier apparatus wherein the means for selectively driving the belt includes a selector switch. Alternatively, the means for selectively driving the belt may include means for disconnecting the belt driving means from the humidifier. Illustratively, the disconnecting means may comprise a connector electrically connected to the belt driving motor and a pair of connectors electrically connected in the control circuit of the humidifier whereby the desired selective operation of the belt driving means is obtained by selective connection of the first connector to either of the two second connectors.

The humidifier may further include means for operating the air moving means at different speeds independently of the belt driving means.

The humidifier may further include means for maintaining operation of the humidifier apparatus notwithstanding a lack of moisturizing liquid whereby the apparatus may further serve as a fan means independently of its moisturizing functioning. The belt means may be selectively operated while the humidifier apparatus is operated as a fan means thereby to function as an air filtering means at such times.

BRIEF DESCRIPTION OF THE DRAWING

Other features and advantages of the invention will be apparent from the following description taken in connection with the accompanying drawing wherein:

FIG. 1 is a schematic vertical section of a humidifier embodying the invention;

FIG. 2 is a vertical section taken substantially along the line 2-2 of FIG. 1;

FIG. 3 is a schematic wiring diagram illustrating the control circuitry thereof; and

FIG. 4 is a schematic wiring diagram illustrating a modified control circuitry thereof.

2

DESCRIPTION OF THE PREFERRED EMBODIMENTS

In the exemplary embodiment of the invention as disclosed in FIGS. 1-3 of the drawing, a humidifier generally designated 10 is shown to comprise a housing 11 defining an internal apparatus space 12 in which is mounted an air moving means comprising fan 13, a container 14 for holding moisturizing liquid, such as water W, and a flexible humidification supply means comprising a belt 15 turned over suitable pulleys 16 and 17. Belt 15 is a driven by a suitable motor 18 to move through a preselected path extending downwardly into the container 14 and forwardly of fan 13. The moisturizing water W absorbed by the belt as it passes through container 14 is dispersed into the stream of air delivered by fan 13 through a front grille 19 for providing humidified air to the ambient atmosphere. Operation of the humidifier is controlled by a conventional humidistat 20 so that operation of fan 13 is effected only when the humidity conditions of the ambient atmosphere drop below a preselected level calling for delivery of moisturized air from the humidifier. Where the humidity conditions are quite low a high speed operation of fan 13 may be effected by means of a selector switch 21. Where the humidifying requirements are not severe, switch 21 may be set to operate fan 13 at a low speed as desired. Heat may be provided under the control of a suitable switch 22, the actuation of switch 22 being indicated by a suitable indicator light 23.

A float control generally designated 24 may be provided having a float 25 movable with the level L of the water W in the container 14. Float 25 is carried on a suitable arm 26 of control 24 to effect operation thereof in controlling the operation of the humidifier. Control 24 may be provided with an indicating lamp 27 for indicating an empty condition in the container 14 thereby to notify the user of the need to replenish the moisturizing liquid. Control 24 may include a suitable electric switch 28 operated by control arm 26 to effect the desired control of the humidifier.

As indicated briefly above, apparatus 10 permits the selective control of belt motor 18 so as to permit the alternative continuous operation of the belt motor or the operation of the belt motor only when the fan is operating. More specifically, as seen in FIGS. 1 and 3, the belt motor may be electrically connected into the control circuit generally designated 29 by means of a first, male connector 30 and a pair of second, female connectors 31 and 32. As best seen in FIG. 3, power may be provided to the humidifier 10 from power supply leads L₁ and L₂. One side of connector 31 is connected to power supply lead L₂ and the other side is connected to power supply lead L₁. Thus, when connector 30 is plugged into connector 31, belt motor 18 is continuously operated.

One side of connector 32 is connected to power supply lead L₂ and the other side is connected to between humidistat 20 and fan motor 13. The other side of fan motor 13 is energized from power supply lead L₂ through selector switch 21 which may comprise a single throw, double pole switch having moving contact 21a connected to power supply lead L₂ and fixed contacts 21b and 21c connected to the different speed windings of the fan motor 13. One side of an electrical heater 33 is connected to power supply lead L₂ and the other side is connected through a single pole, single throw switch 22 to between humidistat 20 and fan motor 13. Heater indicator lamp 23 is connected in parallel with heater 33.

Float switch 28 may comprise a single pole, double throw switch having moving contact 28a connected to power supply lead L₁, a first, fixed contact 28b connected to humidistat 20, and a second, fixed contact 28c connected to indicator lamp 27. A single pole, single throw switch 34 is connected between power supply lead L₁ and humidistat 20 to complete the circuit.

Thus, when belt motor plug 30 is connected to connector 32, the belt motor is effectively connected in parallel with the fan motor 13 and heater 33. Thusly connected, belt motor 18 is operated concurrently with the fan motor under the normal control of the humidifier control 29. Thus, when the humidifi-

stat cycles fan motor 13, it will concurrently cycle belt motor 18.

Switch 34 permits continued operation of the fan motor and belt motor notwithstanding an absence of moisturizing liquid from container 14 as switch 34 effectively bypasses the float switch 28 to connect the humidistat directly to power supply lead L₁. Switch 34, however, will cycle the fan motor and belt motor in accordance with the humidity conditions of the ambient atmosphere and, thus, does not necessarily cause a continuous operation of belt motor 18 unless the humidity conditions remain sufficiently low to maintain humidistat 20 in the closed circuit condition.

Referring now to FIG. 4, a modified form of control circuit generally designated 129 is shown to comprise a control circuit generally similar to control circuit 29 except that the selective connecting means 30, 31 and 32 are replaced by a single pole, double throw selector switch 135 having a moving contact 135a connected to power supply lead L₂ through the belt motor 18. The switch includes a first, fixed contact 135b connected to between the humidistat 20 and the fan motor 13. A second, fixed contact 135c of switch 135 is connected to the other power supply lead L₁.

Thus, manipulation of switch 135 to throw moving contact 135a into contact with fixed contact 135c causes a continuous operation of the belt motor 18 in a manner similar to the connection of belt motor 18 through connectors 30 and 31. Alternatively, when contact 135a is thrown into contact with fixed contact 135b, operation of the belt motor 18 in parallel with fan motor 13 is effected similarly to the operation of control 29 when connector 30 is connected to connector 32 thereof. In all other respects, control 129 is similar to and functions similarly to control 29.

Thus, the invention comprehends an improved humidifier apparatus wherein the problem of drying of belt 15 and the caking of deposited salts thereof is effectively eliminated. Further, the invention permits substantially instant full humidification upon initiation of the fan 13. Thus, operation of the humidifier with a partially dry filter belt 15 is effectively precluded. By maintaining the flexible belt in a flexible condition at all times, maintenance of the apparatus is effectively minimized. The present invention comprehends a simple and

economical construction while yet providing the highly desirable advantages discussed above.

The foregoing disclosure of specific embodiments is illustrative of the broad inventive concepts comprehended by the invention.

I claim:

1. A humidifier apparatus comprising: flexible humidification supply means; air moving means for transferring moisture from said humidification supply means to the ambient atmosphere including means flexing said humidification supply means; and electrical control means selectively disposable for alternatively causing said flexing means to flex said humidification supply means only when the humidification supply means is transferring moisture from said humidification supply means to the ambient atmosphere or at all times, said flexing means comprising electrically operated means and said control means including a first connector electrically connected to said flexing means and a pair of second connectors electrically connected in said control means arranged to provide manual control of said alternative functioning as a result of connecting said first connector alternatively to either of said second connectors.
2. In a humidifier having a belt, and means for moisturizing said belt, means for moving air against said belt and delivering air moisturized thereby to the ambient atmosphere, and means including an electric motor and an electrical control for controlling the operation of the humidifier for selectively driving the belt (a) only whenever the air moving means is operated, or (b) continuously, said control means including means for electrically disconnecting the belt driving means from the humidifier comprising a connector electrically connected to said motor and separably connected to said control.

3. The humidifier apparatus of claim 2 wherein said control means comprises a male plug connected to said motor, a first female socket connected between power supply leads of the control for causing continuous operation of said motor upon energization of said control, with said plug connected to said first socket, and a second female socket connected in said control for causing operation of said motor only when said air moving means is operated by the control with said plug connected to said second socket.
